By Murray Murray Atteys

UNITED STATES PATENT OFFICE

ISAAC A. BAUM, OF CHICAGO, ILLINOIS

COMBINED BUCK AND JAMB

Application filed August 4, 1928. Serial No. 297,454.

My invention relates to building construction and particularly to a framing element for doors and other wall openings.

An object of my invention is to provide an all-metal buck, jamb and stop of the utmost simplicity and of minimum weight of material.

I have in co-pending applications for patents illustrated other forms of all-metal frames involving a channel shaped buck and a jamb, stop and moulding, but such construction involves the use of an excess of material over that required in the design now submitted. In the present construction, I have combined the jamb and buck in one element of channel shape which is snugly fitted over the margin of the tile wall thus insuring the utmost rigidity. To complete the required elements, I provide an angular strip welded to a side flange and shaped to provide a plaster terminal, ground and moulding. Separate strips secured to the inside face of the channel at intervals in the length thereof, serve the double purposes of providing for a wall anchor and as shims for a hinge block.

The invention will be more readily understood by reference to the accompanying drawings, in which—

Fig. 1 is a sectional view through a frame construction in accordance with my invention, and applied to a tile wall, and

Fig. 2 is a side elevation thereof.

In the drawings, a tile wall is indicated at A, and plaster at B.

The device of my invention consists of a continuous channel having a web 10 and side flanges 11. A stop 12 is formed in the web by displacing the metal thereof into the form shown. The channel is so designed that the flanges fit snugly over the sides of the tile wall, and as the flanges are continuous the framing member is in effect a part of the wall, the thrusts and blows incident to the door action being transmitted directly to the wall and not into any fastening devices such as nails or screws.

In order to provide a finish around the opening, I utilize L shaped continuous strips, the one shown in the upper portion in Fig. 50 1 having a foot flange 13 that is welded to

the channel flange 11, and a perpendicular flange 14 having a depth corresponding to the designed thickness of plaster B, the flange terminating in a rebent margin 15 that acts as a plaster anchor. The construction shown in the lower portion of Fig. 1 is similar, having a foot flange 16 welded to the flange 11, a moulded lateral flange 17 and a rebent margin 18. These elements are very simply applied in the shop, being spot-welded at a few points in the length of the frame.

As a means for anchoring the frame against lateral thrusts I provide the T head anchor 19, the shank of which is embedded in the masonry wall and the head of which occupies the space within the stop 12. Short strips 20—21 are welded to the inside face of the web at intervals in the length of the frame. The inner edges of the strips project across the opening into the space within stop 12 and provide an interlock for the T head anchor. The strip 21 extends laterally outwardly and has a cutout to correspond to a cutout 22 in the web of the frame to receive the butt of a hinge. A hinge block 23 is welded to the strip 21 and serves as a mount for the hinge screws. The strip 21 thus serves as a shim for the hinge block and as a means for forming the interlock for the wall anchor.

The parts as described are all formed and welded in the shop and shipped ready for installation. The corner connection is not shown, but is in the form of a sliding interlock such as described in co-pending applications.

The invention is one capable of considerable modification and I do not wish to be limited as indicated in the appended claims.

I claim:

1. In door framing, the combination of a channel shaped member, the flanges of which are adapted to receive the edge of a masonry wall, the web of the channel constituting a jamb, and a continuous angle strip constituting a plaster terminal, ground and moulding welded to the side face of a flange.

2. In door framing, the combination of a channel shaped member, the flanges of which are adapted to receive the edges of a

masonry wall, the web of the channel constituting a jamb, and an L shaped member one leg of which is secured to the side of a flange and the other leg of which acts as a plaster terminal and moulding.

5 3. In framing, the combination of a jamb of channel shape adapted to be directly mounted over the edge of a masonry wall and an L shaped continuous strip one leg of which is welded to the outer face of a flange and the other leg of which defines the thickness of and acts as a terminal for plaster.

10 4. In combination, a channel member, the flanges of which directly engage a masonry wall and the web of which constitutes a door jamb, a hollow stop formed in said jamb, means for partially closing the back opening into the space within said hollow stop, an anchor having a head adapted to enter the 15 space within said stop and to interlock with said closing means, and a hinge block, said closing means serving as a shim for said block.

20 25 In testimony whereof I have affixed my signature.

ISAAC A. BAUM.
